UNITED STATES PATENT OFFICE.

EMMETT DALTON PACKER, OF MINNEAPOLIS, MINNESOTA.

HARVESTER.

1,278,000.

Specification of Letters Patent.

Patented Sept. 3, 1918.

Application filed March 9, 1917. Serial No. 153,702.

To all whom it may concern:

Be it known that I, EMMETT DALTON PACKER, a citizen of the United States, residing at Minneapolis, in the county of Hennepin and State of Minnesota, have invented 5 certain useful Improvements in Harvesters, of which the following is a specification, reference being had therein to the accompanying drawing.

10 The invention relates to harvesters, and more particularly to the class of combined harvesters and shockers, particularly adaptable for the handling of corn.

The primary object of the invention is the 15 provision of a machine of this character wherein the cutting of the stalks, the tying of said stalks into separate bundles and the gathering of the bundles is successfully effected on the continued operation of the

20 machine. Another object of the invention is the provision of a machine of this character wherein the feeding operation, in conjunction with the binder mechanism for gathering 25 the stalks into a bundle, is automatically controlled for momentarily arresting the feeding of the stalks during the passage of the needle about the bundle for the tying of the same, thereby avoiding damage to the 30 needle or the cramping thereof, which would otherwise occur should the stalks be fed while the needle is active.

A further object of the invention is the 35 provision of a machine of this character wherein the stalks, when severed from the stubble, are bundled into sheaves and subsequently ejected, after the tying of the sheaves on to a shock supporting table for the collecting of the sheaves and the tying 40 of the same together for the subsequent delivery of the collected sheaves in shocks from the machine on to the ground in standing position at one side of said machine, the ejecting of the sheaves on to the shock supporting 45 table being effected in a novel manner, and the stalk feeding and binding mechanisms being automatically arrested on the transfer of the sheaves to the table, thereby eliminating damage to the binding 50 needle and the feeding mechanism, and the stalks, in the feeding operation on to the binder deck, being packed for the close bundling thereof into sheaves without the use of packer arms ordinarily employed for 55 this purpose.

A still further object of the invention is the provision of a machine of this character wherein the wrapping of the stalks and blades, which necessarily damages the fodder, is entirely eliminated and also relieves 60 excessive strain upon the draft animals when employing the ordinary turning or revolving table and binding the bundles with the usual shocker as well as eliminate 65 the manual handling of the sheaves and the shock.

A still further object of the invention is the provision of a machine of this character wherein the feeder fingers of the feeding mechanism are of novel form and supported 70 in a novel manner so as to trail during the activity of the binding mechanism of the machine.

A still further object of the invention is the provision of a machine of this character 75 wherein the binder deck is adjustably supported so that the same can be positioned for the carriage of variable lengths of stalks during the feeding and binding operations 80 of the machine.

A still further object of the invention is the provision of a machine of this character wherein the feeding mechanism, the ejecting mechanism, the binder deck and the supporting of the shock carrying table are of 85 novel form to assure perfect operation of the machine.

A still further object of the invention is the provision of a machine of this character 90 wherein the ejector mechanism controls the needle shaft and through the medium of the latter operates the shock table and the arresting of the stalk feeding mechanism.

Other objects will be in part obvious and in part hereinafter fully pointed out.

The invention accordingly consists in the features of construction, combinations of elements and arrangement of parts which will be exemplified in the construction hereinafter described, and the scope of the application of which will be indicated in the appended claims.

In the accompanying drawings:

Figure 1 is a top plan view of the machine constructed in accordance with the 105 invention;

Fig. 2 is a side elevation;

Fig. 3 is a fragmentary perspective view showing the ejecting, binder and feed mechanisms and binder deck;

- Fig. 4 is a fragmentary enlarged plan view showing the connections between the ejecting needle, binding and feeding mechanisms of the machine;
- 5 Fig. 5 is a perspective view of the ratchet control of the shock table;
- Fig. 6 is a fragmentary vertical sectional view through the shock table showing in detail one of its supports;
- 10 Fig. 7 is a fragmentary horizontal sectional view through the stalk feeding mechanism, with the feeding fingers in feeding position;
- Fig. 8 is a view similar to Fig. 7, showing 15 the feeding fingers in trailing position;
- Fig. 9 is a fragmentary sectional view showing the driving gears of the stalk feeding mechanism;
- Fig. 10 is a fragmentary perspective view 20 of one of the adjustable guide bars for the feeder teeth of the stalk feeding mechanism;
- Fig. 11 is an enlarged fragmentary detail view taken on the line 11—11 of Fig. 2, looking in the direction of the arrows;
- 25 Fig. 12 is a detail perspective of the links of the feeder chain;
- Fig. 13 is a perspective view of one of the feeder fingers;
- Fig. 14 is an elevation, showing the frame 30 of the machine partly in section, of the auxiliary jack for supporting the frame on the transfer of the shock from the table;
- Fig. 15 is a section on the line 15—15 of Fig. 14, looking in the direction of the arrows;
- 35 Fig. 16 is a fragmentary perspective view of the binder deck, showing in detail the adjusting lever therefor;
- Fig. 17 is a fragmentary horizontal section 40 showing the mechanism for setting the feeding fingers in operative position.
- Referring to the drawings in detail, A designates generally the body or bed of the machine, which is adjustably supported 45 upon traction wheels 10 and 11, respectively, the latter wheel being located at the standing side of the body or bed and serves as a prime mover for the various working parts of the machine. The wheels 10 and 11 are 50 journaled upon axles 12 which are adjustable in quadrant racks 13 secured to the bed A as usual, while at the front of said bed is a draft device which is in the form of a tongue or pole 14 pivotally supported in 55 a casting or hanger 15, and this casting carries a toothed segment 16 to which is pivoted a throw lever 17 provided with a hand-released spring-held catch 18 for the segment, and to the lever is pivotally connected 60 a link or rod 19 which is also pivoted to the tongue or pole so that on adjustment of the said lever 17 the latter can be vertically raised or lowered and locked in adjusted position.
- 65 Each axle 12 is adjusted in the quadrant
- rack through the medium of the adjusting device 20 which is of the ordinary well known construction so that the bed or body A of the machine can be raised or lowered relative to the ground for the cutting of 70 long or short stalks on the advancement of the machine.
- Arranged at the standing side of the bed or body A is a device for conducting the standing corn to the cutting apparatus and 75 shocking mechanism, which consists of gatherers 21 and 22, respectively, which are formed with flared forwardly protruding tapered ends 23 which project beyond the front of the bed or body A and constitute an 80 entrance between the gatherers, the details of the latter being hereinafter fully described. The gatherer 21 in the wall thereof, which is vertically disposed, has formed therein forwardly inclined spaced 85 parallel slots 24 and co-extensive therewith, which vary in length with respect to each other, are endless stalk gathering chains 25, the same being trained over sprocket wheels 26 fixed to a supporting shaft 27 which is 90 suitably journaled in the gatherer 21. Other sprocket wheels identical with sprocket wheels 26 are suitably journaled on appropriate shafts mounted near the ends of the slots 24 and the chains 25 are trained over 95 these sprocket wheels also. Certain of the links of these chains 25 pivotally support gatherer fingers 28 which are formed with flanged heel extensions 29 which control or automatically set the said gatherer teeth 28 100 in the operation of the chains for bringing the said teeth to gathering position. The wall of the gatherer 21 supports at the points of the turns in the stretches of the chains 25 finger setting devices including 105 guide plates 30 which are fastened to said wall in any suitable manner and bridge the slots 24, each plate 30 being formed with a raceway 31 for the links of the chain. On said plate is carried a pair of cleats 32 110 which engage with the flanged heel extensions 29 of the gathering fingers 28 to move the latter from trailing position to gathering position from without the space between the gatherers 21 and 22 to within the same 115 so that the gathering fingers will be automatically set for the gathering of the stalks during the passage of the same into the gathering space between the gatherers on the advancement of the machine. The 120 gatherers 21 and 22 at their rear ends are continuous and extend inwardly at right angles behind the wheel 11 on the standing side of the frame to provide a sheaf-forming way 33 between the extensions 34 and 125 35 with said gatherers so that the stalks, when severed, will be directed from between the gatherers 21 and 22 through the way 33 on to the bed or body A of the machine for a purpose presently to be described. It will 130

be observed that the extensions 34 and 35 are inclined with respect to the bed A, thus giving the sheaf forming way 33, as a whole, a diagonal position with reference to the bed A, so that all stalks transferred to the way will be brought more effectively into contact with the stalk advancing means carried by the extension 34 and later described. The shaft 27, being mounted adjacent the line of connection between the extension 34 and the gatherer 21 has the same angle of inclination as the extension 34. Therefore, the sprockets 26 which are carried by the shaft rotate in planes to which the shaft is perpendicularly disposed and since these sprockets rotate in such plane, the planes in which the chains 25 travel (the chains driven by these sprockets) must, travel in planes in which the sprockets rotate. This arrangement gives a diagonal disposition to the chains 25 with respect to the bed A, the planes of the chains inclining downwardly toward the forward end of the bed A. This diagonal disposition of the chains 25 operates to elevate the gathered stalks from the time they enter the mouth of the gatherers until they are served, thus making it unnecessary to arrange the bed A as close to the ground as if the chains 25 moved in planes parallel with the bed, when their forward ends at which they begin the gathering operation would then be no lower than their rear ends from which they pass the gathered stalks into the sheaf forming way. The wall of the extension 34 is formed with slots of varying lengths with respect to each other and through which work spaced parallel endless feeder chains 36, each having on certain of its lengths the pivotal fingers 37 which are identical to the fingers 28 for gathering and advancing the cut stalks in the way 33 when the machine is in operation. At the end of each slot contiguous to the point of communication of the way 33 with the gathering space between the gatherers 21 and 22 and adjacent to the point of the turn of the respective chains 36 is a finger setting device constructed as hereinbefore set forth so as to position the fingers 37 on the chains 36 to gathering position when entering the way 33 from without the same, whence they are in trailing position. The chains 37 are trained about sprocket wheels 38 and 39 respectively, the sprocket wheels 38 being fixed to the innermost shaft 27 of the series journaled upon the gatherer 21, while the sprocket wheels 39 are loosely carried upon rock shafts 40 and 41 respectively, which are journaled for movement upon the extension 34. One of the wheels 39 on the shaft 41 is formed with a hub 42 carrying a sprocket 43, over which is trained a sprocket chain 44, the same being also trained over a sprocket 45 fixed to a driven shaft 46 which carries a beveled pinion 47 meshing with a beveled gear 48 fixed upon a counter-driving shaft 49 suitably journaled beneath the bed or body A of the machine, and upon this shaft 49 at one side of the gear 48 is loosely journaled a sprocket 50 which has trained thereover the driving chain 51, the same being also trained over a sprocket 52 fixed to the wheel 11. The sprocket 50 is formed with a clutch member 53 with which engages a companion clutch member 54 splined or otherwise slidably keyed upon the shaft 49 and is acted upon through the medium of a coiled expansion spring 55 supported upon said shaft 49 to hold the clutch member 54 normally in engagement with the clutch member 53, while acting upon the clutch member is a hand operated throw lever 56 which, when actuated, will disconnect the clutch members 53 and 54 from each other so that driving power from the wheel 11 will be shut off or rendered ineffective upon the shaft 49 which, together with the shaft 46 transmits power from the wheel 11 to the feeder chains 25 and 37, respectively, as will be clearly apparent.

Through the medium of a pinion and shaft connection 57^a with the gear 48 is an eccentric disk 57 to which is concentrically connected a pitman or throw rod 58, the same having pivotal connection with the cutter bar 59 of the stalk cutter 60 which is mounted transversely of the space between the gatherers at the point of juncture of said space with the way 33, the cutter bar 59 being slidably supported in any suitable manner and being of the ordinary well known construction, so that it may be reciprocated by the movement of the pitman 58 which, of course, receives its motion from the disk 57. Located within the way 33 is an adjustable sheaf deck 61 which includes a stationary entrance head 62 to which the deck 61 is hinged, and said deck can be raised and lowered at its free end through the medium of an adjusting lever 63 pivoted to a segment 64 mounted upon the bed or body A, the lever carrying the usual hand-released spring-held latch 65 to engage the segment 64 for locking the lever in adjusted position, and on the adjustment of the deck 61 it will properly support long or short stalks relative to the binding mechanism for the bundling of the said stalks into sheaves in a manner hereinafter to be fully described.

The adjustable deck 61 having at opposite ends transverse collars 61^a guides the stalks, when bundled or in sheaves, on to the binding plate form 62^a next to the bed or body A of the machine, and located at one side thereof, inwardly with respect to the feeder chains 36, is the vertically disposed needle shaft 66 of the binding mechanism, which includes the needle 67 and knotter 68 of the usual well known type, the needle 67 being sup-

ported at the upper end of the needle shaft 66 which, at its lower end, is formed with a crank 69 having pivotally connected thereto a grasshopper acting ratchet including the 5 dog or pawl 70 and the throw member 71, the latter being eccentrically pivoted to a beveled gear 72 which meshes with a pinion 73 loosely journaled upon a connecting shaft 74 journaled in a bracket 75 on the bed A 10 and having the fixed pinion 76 meshing with the gear 77 fixed to the shaft 49, the pinion 73 being formed with a clutch member 78 with which engages a companion clutch member 79 splined or otherwise slidably 15 keyed upon the connecting shaft 74, and this companion clutch member 79 is moved through the medium of a clutch lever 80 automatically operated so that motion from the shaft 49 can be intermittently conveyed 20 to the gear 72 which is fixed to the ejector mechanism hereinafter fully described.

The bed or body A is formed with a central circular opening 81 in which is located a shock supporting table 82, the same being 25 movable upon friction rollers 83 journaled at the under side of the bed or body A, and at the periphery of the table 82 are ratchet teeth 84 with which engages the dog or pawl member 70 so that on grasshopper movement 30 thereof the shock supporting table 82 will be rotated in a step by step manner for a purpose presently described.

Arranged contiguous to the needle shaft 66 is a vertically disposed pressure control shaft 85 carrying abutment fingers 86, against which the stalks are gathered for the bundling of the same into sheaves and the subsequent tying of the latter by binding mechanism on motion of the needle 67 and 35 knotted 68 thereof, the shaft 85 being formed at its lower end with an arm 87 which is at right angles thereto and pivoted to the clutch throw lever 80 so that on the rocking of the shaft 85 the clutch 79 will be automatically 40 operated thereby. Surrounding the shaft 85 is a coiled tension spring 88 which returns the abutting fingers to normal gathering position subsequent to the ejecting of the sheaf on to the table 82 by the ejecting mechanism 45 50 hereinafter fully described.

The rocking shafts 40 and 41 are formed with cranks 89 to which are connected adjustable guide bars 90 arranged in alignment with the longer of the feeder chains 55 60 65 36 to act upon the heel extensions of the feeder fingers 37 so as to normally hold the same in non-trailing position or operative to automatically release the same for trailing action when the stalks are packed and the binding mechanism is active for the tying of the stalks into sheaves. The shaft 41 is formed with a latch lug 91 which engages a keeper 92 on the needle shaft 66 when the needle 67 is in normal inactive position so as 65 to prevent the turning of the shaft 41, and

similarly the shaft 40, for holding the guide bars 90 in normal position, as shown in Figs. 3 and 7 of the drawings. On movement of the needle 67, when the shaft 66 thereof is rocked in the binding operation, the shaft 70 75 41 is released to permit the automatic shifting of the guide bars 90 to the position shown in Fig. 8 of the drawings so as to permit the feeder fingers 37 to trail in the way 33, thereby avoiding the packing and bundling of the stalks therein while the binding mechanism is active for the tying of the stalks into a bundle or sheaf. The guide bar 90, at one end, is suitably slotted to accommodate the gears 39. 80

The shaft 41 at its lower end is formed with an arm 93 to which is connected a pitman 94, the same being formed with a loop end 95 for loose play connection with the pin 96 on an arm 97 formed on the needle 85 shaft 66 so that when the needle 67 is returned to inactive position the shaft 41 will be rocked for the positioning of the guide bars 90 as shown in Figs. 3 and 7 of the drawings, whence the catch 91 on said shaft 90 will lock in the keeper 92 and thus hold the bars 90 in their normal position. It will be apparent that on the initial movement of the needle 67 in the binding operation the shaft 41 is freed by the release of the catch 95 lug 91 from the keeper 92 so that the feeder teeth 37 will trail and cause the guide bars 90 to move from normal position shown in Fig. 7 of the drawings to the position shown in Fig. 8 during a half revolution of the 100 gear 72 and on the remaining half revolution the said shaft 41 will be rocked by the reverse movement of the needle shaft 66 when the needle is being brought to inactive position so that the guide bars 90 will be 105 moved to normal position shown in Fig. 7 and locked in such position.

The gear 72 is mounted at the lower end of an ejector shaft 98 which is suitably adjustable as to height and is located at one 110 side of the adjustable deck 61 opposite the needle shaft 66, which is also suitably adjustable as to height, and carried by this shaft 98 are the ejector arms 99 which act upon the bundle or sheaf for the tying thereof by the binding mechanism to eject the sheaf or bundle on to the shock supporting table 82 from the deck 61 in the continued operation of the machine, the shaft 98 being supported in any suitable manner and is 120 held through the medium of the braces 100 mounted upon the base or bed A of the machine and which suitably connect on diametrically opposite sides of an appropriate sleeve member in which the shaft 98 is journaled. 125

On the upper end of the ejector shaft 98 is a stalk head supporter 101 which prevents the falling of the heads of the stalks and the blades thereof during the binding 130

operation and the ejecting of the bundled or sheaved stalks when the machine is active.

At substantially diametrically opposite points on the bed or body A of the machine 5 and rising above the same are uprights 102 to which are connected shock compressing fingers 103 and 104, respectively, which are bent into outwardly arcuate shape so as to be disposed above and correspondingly to 10 the conformation or shape of the table 82 at the periphery thereof so as to act upon the sheaves when ejected from the deck 61 through the throat 105 on to the table 82 for the formation of a shock, the fingers 103 15 being stationarily supported, yet having the requisite resiliency for expansion, while the fingers 104 are swingingly supported, and in this manner the shock in the formation thereof is compressed to pack the sheaves 20 delivered on to the table 82 between the arms 106 extending radially from the elevator post 107, and these arms are pivotally supported upon said post to normally project radially therefrom during the formation of 25 the shock and upon the lifting of the shock the said arms 106 support the shock until the same has been conveyed from the platform 82 on to the ground and thereafter the said arms 106 are automatically tripped to 30 close on their pivots for the release of the same from the shock.

The bed or body A of the machine has suitably supported thereon the elevating crane 108 which is of the usual well known 35 construction and supports hoisting rigging 109 which has connection with the elevator post 107, the rigging 109 being connected with a windlass 110 which is manually operated through the medium of the crank 111 40 by the operator of the machine. The fingers 104 on the delivery of the shock from the table 82 to the ground are adapted to be opened in gate-like fashion, and the same are controlled through the medium of the 45 hand lever 112 having the connection 113 with the post 102 so that the latter will be turned for the opening of the fingers 104 when said lever 112 is released and actuated by the operator of the machine.

50 Mounted at the front corner of the bed or body A of the machine, opposite the standing side thereof, is a bracket 114 through which works an auxiliary post 115, the lower end of which carries a shoe 116 which 55 is loosely connected thereto, and this post is formed with rack teeth 117 meshing with a rack pinion 118 journaled in said bracket 114, the teeth of the pinion 118 being acted upon through the medium of a double reversing locking pawl 119 so that the post 60 can be locked in its raised or lowered position, thereby supporting the bed or body A of the machine when delivering the shock from the table 82 on to the ground. The 65 journal of the pinion 118 is formed with a

hand crank 120 so that said pinion can be rotated for the adjustment of the post 115, as will be apparent.

Suitably supported upon the extension 35 spaced from the ejector shaft 98 is a shaft 70 121, upon which are carried packer arms 122 for the stalks during the bundling thereof and the binding of the same, and this shaft also carries the guard 123 of the binding mechanism for the needle and knoter 75 thereof.

Arranged at convenient points are the twine holders 124 and 125 respectively for the twine utilized in the binding of the 80 stalks and tying thereof and also in the binding and tying of the shock. The binding and tying of the shock are manually executed by the operator when positioned upon the bed or body A of the machine, which latter constitutes a platform about 85 the shock supporting table 82 in said machine.

In the operation of the machine, the same is advanced over a field and the standing stalks in each row will, in proper order, 90 enter between the gatherers 21 and 22, and the feeder fingers 28 on the chains 25 will act upon the stalks to bring the same into position for the cutting operation of the cutting device 60 which includes the reciprocating cutter bar 59. Thereafter the severed stalks will be fed, under the action of the feeder fingers 37, on to the adjustable deck 61 which has been previously positioned relative to the lengths of the stalks either long or short, and these stalks will become packed for the formation of the same into sheaves, whereupon each sheaf will be bound and tied by the binding mechanism for the subsequent delivery of the sheaves on to the shock supporting table 82 through the 100 throat 105 leading thereto. On the packing of the stalks for the completion of the sheaf the pressure thereof will automatically operate the shaft 85 by the abutment of the 105 stalks against the fingers 86 thereon, thereby holding fast the pinion 73 on the connecting shaft 74 so that upon a half revolution of the gear 72 the needle shaft 66 will be operated for the advancement of the needle 115 67 of the binding mechanism for the binding of the sheaf and the movement of the shaft 66 synchronously releases the shaft 41 so that the guide bars 90 for the feeder fingers 37 will be freed from normal position shown in Fig. 7 and moved therefrom to the position shown in Fig. 8 by the heel extensions of said teeth 37, thereby stopping the feed of the stalks during the binding operation. During the movement of the 120 needle shaft 66 the dog or pawl member 70 is advanced for engagement with a tooth 84 of the series on the table 82, and upon the following half revolution of the gear 72 or its completing rotation, the ejector arms 130

99 will act upon the sheaf for delivering the same from the deck 61 through the throat 105 on to the table 82. During this operation the shaft 41 is actuated to bring the guide bars 90 into normal position shown in Fig. 7 from the position shown in Fig. 8 of the drawings for the repeated packing of the shocks upon the deck 61 to form the next sheaf, and the table 82 is rotated a single tooth to receive the next or succeeding sheaf from the deck after the binding thereof by the binding mechanism, and this operation is repeated continuously until the shock supporting deck 82 has been filled with sheaves in the formation of the shock, whereupon the compressing fingers 104 are opened and the hoisting mechanism for elevating the shock after the binding or tying thereof is operated to deliver the shock from the table 82 on to the ground at one side of the machine. When the sheaf is ejected in its passage through the throat 105 the spring 88 becomes active due to the tension thereof on the initial movement of the shaft 85 to reverse the rotation of the shaft to bring the abutting fingers 86 to normal position, and this movement of the shaft automatically disengages the clutch members 78 and 79, thereby disconnecting the shaft 74 for action in driving the gear 72 and thus retarding or stopping the action of the binding mechanism, the ejector and the rotation of the shock supporting table 82 until the next succeeding sheaf has been formed on the deck 61 for the binding thereof and subsequent ejection of the same.

It is of course understood that the body or bed A can be adjusted relative to the ground so as to raise or lower the bed or body for the cutting of long or short stalks when the machine is advanced through the field. The wheel 11 which is known as the bull wheel is the prime mover for the working of the machine, and on the operation of the throw lever 56 the working parts of the machine can be started or stopped at the option of the operator of said machine.

When the bed or body A of the machine is raised or lowered the tongue 14 can be also adjusted accordingly when the lever 17 is actuated.

The tying mechanism comprising the needle 67 and knoter 68 is intended to be of a form suitable for the present invention but its specific construction is not essential to an understanding thereof.

It is to be understood that changes, variations and modifications may be made in the invention such as come properly within the scope of the appended claims without departing from the spirit or sacrificing any of the advantages of the invention.

It is thought that the construction and operation of the invention will be clearly un-

derstood from the foregoing description taken in connection with the illustrations in the drawings and, therefore, a more extended explanation has been omitted.

Having thus described my invention, I claim:

1. In a machine of the character described, a support, wheels therefor one of which wheels is a bull wheel, gatherers arranged at one side of the support, extensions at the rear of the gatherers and disposed right angularly with reference thereto, a shaft journaled adjacent the point of connection between the inner gatherer and its extension, feeder chains carried by the inner gatherer and its extension, sprockets carried on said shaft over which the feeder chains of the gatherer and its extension are trained, rock-shafts in front of the extension of the inner gatherer, sprockets carried by these shafts over which the gatherer chains for the extension are trained, the said rock shafts being provided with cranks, guide bars pivotally connected to the cranks of said rock shafts, a sheaf forming mechanism carried by the support at the ends of the extensions of the gatherers, a sheaf deck between the extensions of the gatherers, fingers carried by the feeding chains on the extensions and held in positive feeding position by the guide bars, clutch controlled means for driving the feeding chains from the bull wheel, and means connected with the sheaf forming mechanism whereby the latter is operated from the clutch controlled means and the guide bars shifted to let the fingers assume a trailing position when the sheaf forming mechanism has received a sufficient quantity of stalks for the forming of a sheaf.

2. The structure of claim 1 further characterized by a sheaf forming mechanism having a vertically disposed shaft at one end of the sheaf deck, the said shaft being provided with abutment fingers, a spring engaging said shaft for holding the abutment fingers thereof in a position to obstruct passage from the sheaf deck, a clutch controlled device connected with said shaft, and with the sheaf forming mechanism to put the latter in operation when the pressure of the stalks being fed is sufficient to overcome pressure of the spring.

3. The structure of claim 2 augmented by the addition of a shock forming table, and means operatively connected with the sheaf forming mechanism and with the shock forming table for moving the latter intermittently when the shaft having the abutment fingers and its clutch controlled device are operated.

4. In a machine of the character described, a support, wheels journaled on said support, one of which wheels is a bull wheel,

a pair of gatherers in parallel relation arranged at one side of the support, extensions at the rear of the gatherers and disposed right angularly with respect thereto, a plurality of feeding chains carried on the inner gatherer, the said chains being in superposed relation to each other, but of variable lengths, feeding chains carried by the extension of the inner gatherer, the said latter chains being also in superposed relation and of variable lengths, feeding fingers carried by all of said chains, means carried by the inner gatherer and further means carried by the extension thereof, whereby 10 the fingers of the feeding chains are shifted to positive feeding position, the fingers having pivotal connection with the feeding chains to permit their assuming trailing positions when not engaged by the said means, 15 an adjustable sheaf deck positioned between the extensions of the gatherers, a severing device arranged at the rear of the gatherers to sever stalks prior to their entrance on the adjustable deck, and connections between 20 the bull wheel and the feeding chains and severing device, whereby all are put in motion.

5. The structure of claim 4 further augmented by the provision of a stationary entrance head at the rear of the gatherers and on which the severing device is carried, the adjustable sheaf deck being hingedly connected to said entrance head, and a hand lever and locking mechanism therefor, 25 whereby the free end of the sheaf deck may

be raised or lowered and held in such raised or lowered position.

6. In a machine of the character described, a support, wheels journaled on said support, stalk gathering means mounted on 40 said support, the stalk gathering means comprising a pair of gatherers and feed chains therefor, the gatherers having right angular extensions at their rear ends, the two extensions being in spaced relation to each other, 45 whereby a sheaf forming way is formed between them, stalk advancing chains carried by the extension of the inner gatherer, rock shafts positioned in front of the extension of the inner gatherer, said rock shafts being 50 provided with cranks, guide bars pivotally connected to the cranks of said rock shafts, a sheaf forming mechanism carried by the support adjacent the extremities of the extensions of the gatherers, a sheaf deck between the extensions of the gatherers, fingers pivotally mounted on the stalk advancing chains and held in positive feeding position by the guide bars, clutch controlled means 55 for driving the stalk gathering mechanism and the stalk advancing chains from one of the aforesaid wheels, and means connected with the sheaf forming mechanism, whereby the latter is operated from the clutch controlled means and the guide bars shifted 60 to permit the fingers to assume a trailing position when the sheaf forming mechanism is engaged in the forming of a sheaf.

In testimony whereof I affix my signature.

EMMETT DALTON PACKER.
